UNITED STATES PATENT OFFICE

ALFRED G. E. KUROWSKI, OF BROOKLYN, NEW YORK, ASSIGNEE TO UNDERWOOD ELLIOTT FISHER COMPANY, OF NEW YORK, N. Y., A CORPORATION OF DELAWARE

TYPEWRITING MACHINE

Application filed September 18, 1925. Serial No. 57,053.

This invention relates to ribbon shifting mechanism for typewriting machines and more particularly to means for controlling the color field of a bichrome ribbon, and to means for silencing the ribbon when typing upon stencils.

It has been customary to normally use the ribbon in its upper or "black" field or stripe, and to manually set the vibrating mechanism to raise the ribbon to lower or "red" field when desired, so that the lower or "red" field of the ribbon is used. When typing in this lower field, the ribbon has to be raised considerably higher than when typing in upper field; and since the raising of the ribbon is effected through mechanism actuated by the universal bar, which is in turn operated by the keys, it tends to make the key depression hard and uneven, which, of course, is objectionable.

One of the features of this invention relates to means whereby this objection may be overcome. To this end, mechanism is provided whereby the ribbon is manually raised to the printing line preparatory to typing in lower field, from a position considerably below the printing line when typing in upper field. In this manner the "touch" of the keys is improved because the ribbon is raised approximately the same amount when typing in either the "black" or "red" field, and consequently about the same effort is required to depress the keys.

In order to select the color field of the ribbon there is provided a lever near the keyboard. By means of this lever a link, which is operatively connected to the universal bar, is thrown into engagement with either extreme of a slot, controlling the length of the operating arm of the ribbon vibrating lever, so as to change the throw of the ribbon according to color-field. However, in order to compensate for the length of the throw and thus regulate the pressure on the key-levers, there is provided a compensating mechanism which is set by the lever so as to elevate the ribbon when the lever is moved to correspond with the "red" color of the ribbon.

Another feature of this invention relates to novel means whereby the ribbon may be

silenced for typing upon stencil sheets, said means are selectively controlled by positioning the color-field controlling lever in its normal position, thus rendering the vibrating lever ineffective to raise the ribbon.

Other features and advantages will hereinafter appear.

In the accompanying drawings,

Figure 1 is a cross-sectional view in elevation through the center of an Underwood portable typewriting machine having the invention applied thereto.

Figure 2 is a plan view showing the ribbon field control lever in its normal or "black" color-field.

Figure 3 is a front view in elevation showing the ribbon controlling mechanism in its normal position and set for the upper color-field of the ribbon.

Figure 4 shows the operated position of the ribbon for the setting shown in Figure 3.

Figure 5 is a perspective view of the manually operated ribbon raising mechanism.

Figures 6 and 7 are front views in elevation showing respectively the normal and operated positions of the ribbon controlling mechanism as set for the "red" or lower field of the ribbon.

Figure 8 is a plan view showing the normal position of the ribbon vibrating mechanism as set for the "red" or lower field of the ribbon.

Figure 9 is a plan view showing the neutral setting of the ribbon controlling lever in its normal position.

In the Underwood portable typewriting machine, in connection with which this invention is illustrated, there is provided a universal bar 10 mounted upon a rock-shaft 11, and swung downwardly against a spring 12, upon depressing any of a plurality of keys 13. Said keys are fast to key-levers 14, mounted upon a fulcrum plate 15, having a plurality of springs 16 operatively connected for restoring the key-levers to their normal position. Each key is, of course, operatively connected to a type-bar 17 by mechanism, not shown, but effective to swing the type-bars at the depression of associated key-levers.

Since the ribbon mechanism forming the

100

subject of this invention is provided for the purpose of covering the printing point upon depressing the keys, and, since the universal bar in the machine is operative to letter-space the carriage at the depression of each key, it has been found advisable to connect the said ribbon vibrating mechanism to said universal bar. To this end, the shaft 11 is secured to the arms 18 of the universal bar so as to rock therewith, the shaft being journaled in brackets 19 fast to a cross-bar 20 in turn fast to the frame of the machine.

Upon the shaft 11 and secured thereto by means of a screw 21 there is provided an arm 22 which extends upwardly and has at the end thereof a stud 23 upon which there is rockably mounted a universal joint 24 which carries a link 25. Said link 25 is pivotally mounted at 26 upon the joint 24, and terminates with a threaded portion 27 which threads into a rocking member 28 thus providing an adjustment for the effective length of the link 25. The member 28 is operatively connected to a rocking lever 29 pivotally mounted on a stud 30 fast to a bracket 31 secured to the frame of the machine by means of a screw 32. The lever 29 is provided with a circumferential slot 33 for receiving a turned down portion 34 of said member 28, the center of the radius of the slot being substantially upon the fulcrum 26 of the link 25 in order to facilitate the moving of the link from one end to the other of the slot, as shown in Figures 2 and 8.

Since the universal bar 10 has a uniform movement at each key depression, the arm 22, which is secured to the shaft 11, will have a uniform throw at each key depression, from which it follows that, if the link 25 is shifted to engage opposite ends of the slot 33, the swing of said lever 29 will vary proportionately. The slot 33 is provided with a recess or cut 35 at the center thereof into which the part 34 may vibrate when the link 25 is shifted to an intermediate position to render the lever 29 ineffective.

In order to move the link 25 in cooperating position with either end of the slot 33 or with the cut 35, there is provided a manually operable lever 36 rockably mounted upon a stud 37 fast to a bracket 38 in turn secured to the frame of the machine by means of a screw 39. Said lever 36 is provided with a finger-piece 40 at the end thereof, and has a detent 41 formed therein for engaging with notches 42 in the front plate 43, each notch corresponding to one of the three positions of the member 28 in the slot 33.

In said Underwood machine, the ribbon vibrator is operable by all of the type-keys, and since some of the type-keys are operated in lower-case position of the platen and other keys are operated in the upper case position, it follows, that certain of the mechanism for operating the ribbon mechanism must be on

the main frame, whereas the ribbon vibrator itself and certain actuating means therefor must be mounted on the shift frame. One of the features of this invention relates to novel means for connecting the vibrator or lever 29 on the main frame to the mechanism on the shift frame. Referring more particularly to Figures 3, 4, 5, 6 and 7 in which several operating views are shown of the mechanism mounted on the shift frame it will be noted that there is provided an operating lever or vibrator 44 fulcrumed upon a stud 45 fast to the carriage shift frame 46 and that the lever is operatively connected to a ribbon carrier 47 by means of a pin 48 on the carrier engaging with a slot 49 in said lever 44. The ribbon carrier is provided with fingers 50 having slots 51 through which is passed a bichrome ribbon 52, the colors thereof being indicated respectively by the numerals 53 and 54, the former representing the upper field or "black" and corresponding to the identification color field represented by the numeral 55 which represents a corresponding position of the lever 36, shown in Figure 2.

In order that the lever 44 which is mounted on the carriage shift frame may be moved to upper case position without severing the operating connection with the operating lever 29, the latter is provided with a channel 56 formed by upwardly extending walls 57 forming an integral part of the lever 29. The channel 56 is vertically disposed in cooperating relationship with an operating stud 58 which forms a part of a toggle system operatively connected to the lever 44 to raise the ribbon at each key depression.

According to one of the features of this invention, it is desired to manually raise the ribbon carrier up to the printing line, as shown in Figure 6, from a position much below the printing line shown in Figure 3, preparatory to writing with the lower or "red" field of the ribbon. To this end, there is provided mechanism operatively mounted on the carriage shift frame, designed to elevate the ribbon when the lever 36 is swung from "black" to "red" position. Said mechanism includes a sliding cam-plate 59 having a bent portion 60 at the end thereof, the bent portion engaging with two fingers 61 forming an integral part of a rearwardly extending arm 62 of the lever 36. Because of the connection between the plate 59 and the lever 36 when the latter is operated from "black" to "red", the plate is moved to a position as shown in Figures 6 and 7. The lever 29 is operatively connected to the lever 44 by means of a flexed toggle-joint or linkage including upper and lower arms respectively numbered 63 and 64. The upper arm has the stud 58 fast thereto, which serves as a fulcrum for the lower arm 64. Referring to Figure 5 in which a dismembered perspec-

tive view of the toggle-joint is shown, it will be noted that there is provided a stationary plate 66 secured to the carriage shift frame 46 by means of screws 67 through holes 68 in said plate, and that the supporting point of the lower arm 64 carries a stud 69 which passes through a vertical slot 70 in the stationary plate and a horizontal slot 71 in the sliding plate. Since it is one of the objects of the sliding cam-plate 59 to elevate the ribbon when the plate is slid from one position to another, the plate is provided with inclined slots 72 designed to engage with supporting studs 73 fast to the fixed plate 66. Said studs 73 serve as a guide for the plate 59 which elevates the stud 69 when moving to the left because of the inclination of the slots 72. The upper end of the arm 63 is operatively connected to the lever 44 by means of a stud 74 which passes through a hole in said lever and is screwed into a tapped hole 76 in the arm 63.

Since it has been shown that there is provided mechanism for elevating the ribbon preparatory to typing in the lower field thereof, and also mechanism for vibrating the ribbon at each key depression, it will be apparent that both mechanisms must be tied together in order to synchronize their operation. To this end, there is provided a link 77 operatively connecting the link 25 with the rearwardly extending arm 62 of the lever 36, which controls the ribbon elevating mechanism by means hereinbefore described. Said link 77 may be connected to the link 25 by means of a stud 79 and to the lever 36 by means of a stud 78, so that when the lever is swung from one position to the other, the piece 28 will be moved to either end of the slot 33, as shown in Figures 2 and 8.

It will be understood that this invention is illustrated in connection with an Underwood portable typewriting machine having three positions of a platen 80, the two upper positions being indicated in dot-and-dash lines, and each position of the platen corresponding to co-operating types in the type-bars. In this type of machine the platen is revolubly mounted on a carriage 81 slidably mounted on the carriage shift frame by means of rollers 82 and 83. The platen may be shifted to the different positions by mechanism such as that disclosed in the Patent No. 1,297,085 to L. S. Burridge, dated March 11, 1919.

It will be noted that the lever 44 has a permanent fulcrum 45; that the fork-formations 56 and 61 are compensating driving connections for the case-shifted stud 58 and the tongue 60 respectively; and that the shift-lever 36 is effective through its connections with the vibrator to lengthen a normal stroke for the upper field of the ribbon and to shorten a normal long stroke for the lower field of

the ribbon, that both fields may be vibrated by a more uniform typing effort at the keys.

Variations may be resorted to within the scope of the invention, and portions of the improvements may be used without others.

Having thus described my invention, I claim:

1. The combination with a typewriting machine having a main frame, a shift-frame, a vibrating member operated by the typing elements of the machine, and ribbon-vibrating mechanism operatively connected to said vibrating member for selectively vibrating either field of a bichrome ribbon, of means including a manually-operable lever pivoted on said main frame for setting the ribbon-vibrating mechanism according to the field of the ribbon to be used, and instrumentalities on said shift-frame controlled by said lever to raise the ribbon preparatory to vibrating the ribbon in lower field, said lever being slidably connected with said instrumentalities, so as to permit free upward movement of the latter.

2. The combination with a typewriting machine having a main frame, a shift-frame, a vibrating member operated by the typing elements of the machine, and ribbon-vibrating mechanism on said shift-frame operatively connected to said vibrating member for selectively vibrating either field of a bichrome ribbon, of means including a manually-operable lever laterally movable about a pivot on said main frame for setting the ribbon-vibrating mechanism, and a laterally-movable cam-carrying device controlled by said lever to raise the ribbon to the printing line preparatory to vibrating the ribbon in lower field, said device being also effective to lower the ribbon below the printing line preparatory to vibrating the ribbon in upper field, said lever being slidably connected with said device to permit up and down movement of the latter.

3. The combination with a typewriting machine having a vibrating member operated by the typing elements of the machine, and ribbon-vibrating mechanism operatively connected to said vibrating member for selectively vibrating either field of a bichrome ribbon, and means including a manually-operable lever for setting the ribbon-vibrating mechanism, of means controlled by said lever to raise the ribbon to the printing line preparatory to vibrating the ribbon in lower field, said last-mentioned means including a vibrating lever operatively connected to the ribbon, a toggle-system of levers having the actuating point mounted on said vibrating lever and the fulcrum point movable upwardly and instrumentalities for maintaining said points in approximately the same angular relation with the toggle-joint when said ribbon is raised preparatory to vibrating it in lower field, whereby the same force will actuate said

toggle-system when said ribbon is being vibrated in either field.

4. The combination with a typewriting machine having a series of key-controlled type-bars, a universal bar operated by said keys, and a ribbon-vibrating mechanism operated by said universal bar including a toggle-system and a ribbon-supporting lever actuated by said system, of a manually-operable lever for controlling the color-zone of a bichrome ribbon, means supporting said toggle for raising the normal position of the ribbon preparatory to typing in the lower field thereof, said means including linkage operatively connecting said manually-operable lever to the ribbon-vibrating mechanism, a vertically-sliding connection between said last-named lever and said means, and a vertically-sliding connection between said ribbon-vibrating mechanism and said ribbon-supporting lever.

5. The combination with a typewriting machine having a platen and a bichrome-ribbon-vibrating mechanism including a vibrator having a permanent fulcrum, of means for selectively controlling said vibrator to predetermine the color-zone presented to the platen in typing and including a shiftable hand-lever, said means also including a horizontally disposed diagonally movable cam-plate and connections intermediate said cam-plate and said vibrator to raise the normal position of the ribbon up to the typing line of the platen preparatory to typing with the lower color-zone of the ribbon from a position below the typing line, from which position the ribbon is normally vibrated when typing in the upper color-zone thereof.

6. The combination with a typewriting machine having a universal bar and a ribbon-vibrator, of means for controlling the color-zone of a bichrome ribbon, and instrumentalities controlled by the color-zone-controlling means to raise the position of the ribbon-vibrator to bring the ribbon to the printing point preparatory to typing with the lower color-field of the ribbon from a position below the printing point in which the ribbon is normally held when typing in the upper color-field thereof, said instrumentalities including a toggle-joint-operated lever connected with said vibrator and a cam-plate disposed for angular travel in a vertical plane and carrying thereon the fulcrum of the toggle-joint, said plate being operatively connected to the color-zone-controlling means.

7. The combination with a typewriting machine having a universal bar and typing instrumentalities, which vibrate said universal bar, of means for controlling the color-zone of a bichrome ribbon, said means including a manually-operable lever movable in a horizontal plane, a ribbon-vibrator, a ribbon-vibrator lever, and means controlled by said first-named lever for raising the ribbon-vibrator preparatory to typing with the lower

field of the ribbon and for lowering the same preparatory to typing with the upper color-field thereof, said last-mentioned means including a variable throw lever controlled by the universal bar, a toggle-joint operatively connecting said last-mentioned lever to the ribbon-vibrator lever, and a plate for carrying the fulcrum of said toggle-joint, said plate being operatively connected to said manually-operable lever controlling the color-zone of the ribbon.

8. The combination with a typewriting machine having a platen and a bichrome-ribbon-vibrating mechanism including a vibrator having a permanent fulcrum, of means for selectively controlling said vibrator by predetermining the normal position of the ribbon below the typing line of the platen, from which position the ribbon may be vibrated to present a color-zone thereof to the typing line, said means including a shiftable hand-lever, a longitudinally shiftable horizontally disposed cam-plate, and connections intermediate said cam-plate and said vibrator displaceable with the cam-plate and effective to raise the normal position of the ribbon up to the typing line of the platen preparatory to presenting the lower color-zone of the ribbon to cover the typing line of the platen.

9. In a typewriting machine having a shift-frame, the combination with a ribbon-carrying member mounted for vibrating a bichrome ribbon at the printing point of said machine, of a vibratory lever laterally disposed in a vertical plane and having one end pivotally fastened to said ribbon-carrying member and its opposite end pivoted to said shift-frame, a vertically-disposed laterally-movable plate mounted on said shift-frame and having angularly-disposed cam-slots, studs supported on said shift-frame and engaging in said slots, so that said plate may be raised or lowered upon lateral movement thereof, instrumentalities connecting said plate and said lever, whereby lateral movement of said plate will raise said lever and said ribbon-carrying member, so that the lower color-field of said bichrome ribbon will be disposed in an upper vibrating position adjacent the printing point, and manually-operable means for moving said plate laterally.

10. In a typewriting machine having a shift-frame and a main frame, the combination with a ribbon-carrying member mounted for vibrating a bichrome ribbon at the printing point of said machine, of a vibratory lever laterally-disposed in a vertical plane and having one end pivotally fastened to said ribbon-carrying member and its opposite end pivoted to said shift-frame, a vertically-disposed laterally-movable plate mounted on said shift-frame and having angularly-disposed cam-slots, studs supported on said shift-frame and engaging in said slots, so that

5 said plate may be raised or lowered upon lateral movement thereof, instrumentalities connecting said plate and said lever, whereby lateral movement of said plate will raise said lever and said ribbon-carrying member, so that the lower color-field of said bichrome ribbon will be disposed in an upper vibrating position adjacent the printing point, a manually-operable lever pivoted on said main frame for lateral movement, a sliding connection between said last-mentioned lever and said plate to permit said plate to be raised vertically, and latching instrumentalities on said main frame for engaging said last mentioned lever to hold it and said plate in a plurality of positions.

10 11. In a typewriting machine having a main frame and a shift-frame, the combination with a ribbon-carrying member for vibrating a bichrome ribbon at the printing point of said machine, of a lever laterally disposed in a vertical plane and having one end pivotally fastened to said ribbon-carrying member and its opposite end pivoted on a shift-frame, a vertical plate fast on said shift-frame and provided with a substantially vertical open slot extending upwardly from its lower edge, two studs fast in said plate, one on either side of said slot, a laterally-slidable plate disposed against said vertical plate and provided with two parallel inclined slots arranged for engaging around studs, and a horizontal slot disposed between said inclined slots and lying across said open slot, a pin disposed in said open slot and extending forwardly through said horizontal slot, a toggle-device having its fulcrum on said pin and its operating end pivoted to said lever intermediate the ends thereof, and a vertical guide for the joint of said toggle, whereby upon lateral movement of said slidable plate and the raising of the same by co-operation of said studs and said inclined slots, said pin and said toggle-device will also be raised approximately vertically and will swing said lever upwardly and dispose said ribbon in an upper initial vibrating position.

15 12. In a typewriting machine having a shift-frame and typing instrumentalities, in combination, a vibrator for a bichrome ribbon having an upper initial vibrating position for the lower color-band of said ribbon, a laterally-disposed lever having one end pivoted on said shift-frame to permit up and down movement of its free end, which is pivotally fastened to said vibrator, a toggle disposed in a vertical plane and having a fulcrum movable upwardly and downwardly and its operating end pivotally fastened to said lever intermediate its ends, a pin projecting forwardly through the joint of said toggle, means for vibrating said toggle laterally upon operation of said typing instrumentalities, said means including a member

arranged for lateral vibration and having a vertical guide-channel engaging around said pin, whereby, upon moving the fulcrum of said toggle upwardly, said lever and said vibrator will be raised to bring the latter to its upper vibrating position without adversely affecting the vibrating action of said toggle.

20 13. In a typewriting machine, in combination, a universal bar and a ribbon-vibrating mechanism operated by said universal bar, said mechanism including a vibratory member, a vibrating toggle having its operating end pivoted to said member and a fulcrum movable toward said member, and a guide for the joint of said toggle disposed substantially parallel to a line through said fulcrum and said operating end, so that movement of said fulcrum toward said member will move said member substantially the same amount with the angular relation of the arms of the toggle remaining substantially unchanged, whereby said member may be vibrated in its new position by the same force as is required in its first position.

25 14. In a bichrome ribbon mechanism for a typewriting machine, the combination with a ribbon-vibrator normally operative to vibrate one field of the ribbon to cover and uncover the typing position on the platen at each key-stroke in typing, of manually settable means connectible, at will, to reset the normal position of the ribbon to the typing line and proportionately reduce the extent of key-actuated vibration thereof necessary to present the other field of the ribbon to the typing position to provide a substantially uniform touch for the keys.

30 15. In a bichrome ribbon mechanism for a typewriting machine, the combination with a ribbon-vibrator normally operative to vibrate the upper field of the ribbon from a normal position to a typing position on the platen at each key-stroke in typing, of manually settable means connectible, at will, to reset the vibrator and ribbon towards the typing line to establish a new normal position therefor and proportionately reduce the key-actuated throw of the vibrator necessary to present the lower field of the ribbon to the typing line to provide a substantially uniform touch for the keys.

35 16. In a ribbon mechanism for a typewriting machine, the combination with a key-actuated ribbon-vibrating mechanism for a bichrome ribbon operative to vibrate one color zone of the ribbon from a normal position to the typing position prior to each typing impact, of settable controlling means operatively connected to said ribbon-vibrating mechanism to change the normal position of the ribbon and simultaneously change the normal throw of the ribbon to vibrate the other color zone of the ribbon to the typing position with

a proportionate reduction in the typing effort at the keys.

17. In a ribbon mechanism for a typewriting machine, the combination with a key-actuated ribbon-vibrating mechanism for a bi-chrome ribbon operative to vibrate one color zone of the ribbon from a normal position to the typing position prior to each typing impact, of a manually operable shiftable lever having a plurality of connections to the ribbon-vibrating mechanism, one connection being operative to change the normal position of the ribbon, and other connections being operative to effect a change in the normal throw of the ribbon, and all the connections being jointly effective to present the other color zone of the ribbon to the typing position and reduce the typing effort at the keys.

18. In a ribbon mechanism for a typewriting machine, the combination with a key-actuated ribbon-vibrating mechanism for a bi-chrome ribbon, of a hand-lever shiftable between two extreme positions for variably controlling the ribbon-vibrating mechanism, and connections intermediate the hand-lever and the vibrating mechanism, said lever when shifted to one position being effective through said intermediate connections to establish a normal position and a normal throw for the ribbon to present the upper color field thereof to the typing position and said lever when shifted to the other position being effective to simultaneously establish a new normal position and a longer throw for the ribbon to present the lower color field of the ribbon to the typing position with a substantially uniform typing effort at the keys.

19. In a typewriting machine having a frame, the combination of a platen-frame shiftable up and down to case-shift positions and having a ribbon-vibrator pivotally mounted thereon, a flexed toggle pivotally connected with the vibrator, a slidable cam-plate mounted upon the shift-frame to pivotally anchor one end of the toggle, a lever swingable about a pivot of the machine-frame and operatively connected to mechanism uniformly vibrated by any key-lever in typing, said lever having a driving connection with the toggle to straighten out the toggle at any case-shift position thereof, to actuate the ribbon-vibrator to present a ribbon-field to the typing position, and a hand-lever operatively connectible at either position of the case-shift frame to vibrate the cam-plate and change the operative scope of the toggle to vary the throw of the ribbon-vibrator.

20. In a typewriting machine having a frame, the combination of a platen-frame shiftable up and down to case-shift positions and having a ribbon-vibrator pivotally mounted thereon, a flexed toggle pivotally connected with the vibrator, a slidable cam-plate mounted upon the shift-frame to pivotally anchor one end of the toggle, a lever

swingable about a pivot of the machine-frame and operatively connected to mechanism uniformly vibrated by any key-lever in typing, said lever having a driving connection with the toggle to straighten out the toggle at any case-shift position thereof, to actuate the ribbon-vibrator to present a ribbon-field to the typing position, and a hand-lever operatively connected to a part of the key-vibrated mechanism to vary the translation of motion therefrom to said swingable lever to increase the throw thereof in straightening out the toggle, to present another ribbon-field to the typing position at either case-shift position of the platen.

21. In a typewriting machine having a frame, the combination of a platen-frame shiftable up and down to case-shift positions and having a ribbon-vibrator pivotally mounted thereon, a flexed toggle pivotally connected with the vibrator, a slidable cam-plate mounted upon the shift-frame to pivotally anchor one end of the toggle, a lever swingable about a pivot of the machine-frame and operatively connected to mechanism uniformly vibrated by any key-lever in typing, said lever having a driving connection with the toggle to straighten out the toggle at any case-shift position thereof, to actuate the ribbon-vibrator to present a ribbon-field to the typing position, and a hand-lever operatively connected to vibrate the cam-plate to change the operative scope of the toggle and having another connection to a part of the key-vibrated mechanism to increase the motion derived therefrom to increase the swing of the toggle-straightening lever, both connections from said hand-lever co-operating in presenting another ribbon-field to the typing position at either case-shift position of the platen.

ALFRED G. F. KUROWSKI.
